UNITED STATES PATENT OFFICE.

JAMES BARRINGHAM, OF DETROIT, MICHIGAN.

DESIGN FOR A GAME-BOARD.

48,301.

Specification for Design.

Patented Dec. 21, 1915.

Application filed August 24, 1914. Serial No. 858,330. Term of patent 3½ years.

To all whom it may concern:

Be it known that I, JAMES BARRINGHAM, a citizen of the United States, residing in Detroit, in the county of Wayne, State of Michigan, have invented a new, original, and ornamental Design for a Game-Board, of which the following is a specification, reference being had to the accompanying drawing, forming part thereof.

mental portion of the base adjacent a portion of one of the figures. Fig. 3 is a section taken on line 3—3 of Fig. 1. Fig. 4 is a section taken on line 4—4 of Fig. 1.

I claim:

The ornamental design for a game board, as shown.

JAMES BARRINGHAM.
